UNITED STATES PATENT OFFICE.

BORIS DUBI, OF BRIDGEPORT, CONNECTICUT, ASSIGNOR TO RAPID BUTTON ATTACHING MACHINE CO., OF NEW YORK, N. Y., A CORPORATION OF NEW YORK.

BUTTON-FEEDING DEVICE.

1,217,926.

Specification of Letters Patent.

Patented Mar. 6, 1917.

Application filed September 2, 1916. Serial No. 118,165.

To all whom it may concern:

Be it known that I, BORIS DUBI, a subject of the Czar of Russia, and a resident of the city of Bridgeport, county of Fairfield, and State of Connecticut, have invented a new and useful Improvement in Button-Feeding Devices, of which the following is a specification.

The object of my invention is to provide a button feeding device which may be used for any suitable purpose, and particularly upon the type of machine shown in Kotkovsky Patent No. 1,182,019, granted May 9th, 1916. A further object is to provide means for feeding a button directly into the machine without regard to the hopper so that buttons of a different nature from those in the hopper may be fed to the machine when desired, so that different buttons may be put on special jobs, as occasion may require without the necessity of emptying the hopper and refilling the same with the type of button to be applied to the job. These and other objects are accomplished by my invention, one embodiment of which is hereinafter more particularly set forth.

Figure 1 is a side elevation of my improved device, parts being shown in section.

Fig. 2 is a sectional view of the mechanism for elevating the feeding device.

Fig. 3 is a plan view of the structure shown in Fig. 1.

Figs. 4 and 5 are side elevations of the structure shown in Fig. 1, the elevations being taken on the opposite sides of the apparatus and showing the parts in different positions.

Fig. 6 is a plan view of a portion of the gate.

Fig. 7 is a sectional view, taken on the line 7—7 of Fig. 4, looking in the direction of the arrows.

Throughout the various views of the drawings, similar reference characters designate similar parts.

My improved button feeding device 1 is mounted on a chute 2 which extends from a hopper or button container of any suitable kind, a portion of such a container being shown at 2^a in Fig. 1. The chute 2 has an inclined grooved edge 3 on which is mounted a suitable guard 4 which is preferably secured to the sides of the chute by bent over lugs 4^a which are bent over and attached thereto by the screws 5^a. The

guard 4, near its upper end, has a pivoted trap 5 which has its free end normally kept against a projection 6 on the guard-rail 4 by a suitable coiled spring mounted on its pivot 7 in the bracket 8, as indicated, said bracket being secured to the side of the chute, and the lower end of the trap 5 has a suitable slot 9 which is adapted to receive a shank of a button immediately over the groove 10 in the edge 3 of the chute 2, so that when a button of the kind ordinarily used in the machine, as an ordinary shoe button, is placed with its lower edge against the projection 6, and its shank in the slot 9, the trap 5 may be depressed and the button is slid down the chute under the guard 4, as is obvious.

The button feeding device 1 cooperates with a hinged gate 11 pivotally mounted between ears 12, see Fig. 6, by the pin 12^a at the lower end of the guard 4, and a coil spring 13 surrounding the pivot pin 12^a, normally keeps this gate in its depressed position so that it rests flat on the lower end of the guard 4 as shown in Figs. 1, 4 and 5. The free end of the gate 11 is bent downwardly as indicated and slotted as at 14 through which the feeding device 1 may intrude, as will be described below.

The feeding device 1 is driven from the reciprocating staple former 15 which may be driven by any suitable mechanism 16, such as is shown in the Kotkovsky patent heretofore mentioned, or otherwise, as desired. It is sufficient for the purposes of this case to state that the reciprocating staple former 15 is driven in the direction of its length, and both ways, by the mechanism 16, as is apparent. This reciprocating staple former 15 is recessed at 17 with a sufficiently long recess to enable a period of dwell to occur between the ends of the reciprocating movement, so that the button feeding device 1 will operate at the right time and not otherwise. An arm 18, pivoted at 19 adjacent its center on the chute 2, has its lower end entering the recess 17 and is actuated by the end walls thereof, as above indicated. The pivot 19 carries a corresponding arm 20, see Fig. 1, on the other side of the chute 2, and the arms 18 and 20 are connected at their upper ends by a pivot 21, see Fig. 7, on which is mounted a curved and pivoted finger 22. A coil spring 23 surrounds the pin 21 and has one of its ends pressing against the fin- 110

ger 22, and its other end bears against a pin 24 fixed in the arm 20 so that the finger 22 is normally kept depressed. The lower end of the finger 22 is bifurcated so as to enter 5 into the slots 14 in the end of the gate 11, and the lower end of said finger 22 is curved as shown at 25 so as to fit the top of a button and move the same forward when the finger is actuated. The lower end of the guard 4 is 10 slotted to register with the slots 14 to permit the lower end 25 of the finger 22 to engage the button 26 through the slots and move the same out from under the guard 4 as hereafter mentioned.

15 The upper surface of the finger 22 is provided with a lug 27 which is adapted to engage a lever 28 which is connected to the mechanism, for feeding the wire which attaches the buttons, not shown, so that when 20 no button is in place, no wire will be fed, as set forth in the Kotkovsky patent heretofore mentioned. It is obvious that this lever 28 is elevated by the lug 27 and swings on its pivot 29, but will not swing sufficiently 25 to cause the wire feeding device to be actuated unless a button 26 is in place and ready to be attached.

To cause the finger 22 to be raised on its return movement so as not to interfere with 30 any button which may be at the bottom of the chute 2, and in front of the gate 11, the following mechanism is employed. Mounted on top of the guard 4 is a suitable stop and cam 30, which is secured to the guard in 35 any desired manner, as by an upwardly turned ear 31 and screws 32, as shown in Figs. 4 and 5. Extending laterally from this stop 30 and near the lower end thereof, is a suitable cam pin 33, the purpose of 40 which will appear below. The lower surface of the finger 22, near the cam pin 33, carries a suitable bearing 34, see Fig. 2, in which is mounted the cam roller 35 which is free to turn in the bearing 34 and adapted to 45 run over the cam surface 36 of the stop 30, except when elevated therefrom by an elevating arm 37 which is made with a socket 38 at its free end to engage the pin 33 and ride thereover and turn thereon so as to elevate the finger 22. The other end of the arm 50 37 is pivotally mounted on a pivot 38 which is mounted in the ears 39, which are secured at 40 to the bearings 34. Suitable coil springs 41 and 42 tend to keep the arm 37 in 55 the elevated position shown in Fig. 2, and allow this arm to be brought closer to the cam roller 35 on the forward movement of the arm 22. On the rearward movement this arm 37 engages the pin 33 and lifts the 60 finger 22 upwardly so that the end 25 of finger is clear of the button 26 which it has moved forward and takes its proper position so as to be ready to move the next button when again actuated, as above set forth.

65 In view of the foregoing, the operation of

my improved device will be readily understood. If it is desired to attach a different type of button than those in place in the chute, the chute can be emptied by moving the buttons that are in it downwardly and 70 out under the gate 11 which is allowed to rise for that purpose, until the chute is emptied. Then the button feeding device is disconnected at or near the hopper, not shown, so as to render the hopper inoperative 75 and then the buttons to be attached are placed, as above described on the trap 5 and inserted into the chute under the guard 4. When it is desired to feed the buttons to the attaching mechanism they are fed by the 80 finger 22 which engages their upper surfaces and forces them out under the gate 11, as above described and into place, and then the lug 27 raises the lever 28 so as to permit wire to be fed through the eye of the button 85 in the manner set forth in the Kotkovsky patent. Thereafter the buttons are stapled to the shoe or other article in the usual way. On the rearward movement of the reciprocating staple former 15 the finger 22 is actuated so as to move the button engaged by it, 90 forward, so as to be ready for the next operation of the attaching apparatus, and on the forward movement of this staple forming mechanism 15 the arm 18 is thrown with 95 its lower end going forward and its upper end toward the rear, as shown in Fig. 4, and this brings the finger 22 toward the rear until the arm 37, which is connected therewith, as heretofore mentioned, strikes the 100 pin 33 and then the finger 22 is elevated so as to clear the button it has moved forward and it assumes its proper position and is ready for the next action of the apparatus. Except when the finger 37 is active and lifting 105 the finger 22, as above described, the spring 23 holds the cam roller 35 against the cam surface 36, which determines the direction of movement of the finger 22 with regard to the button 26.

110 While I have shown and described one embodiment of my invention, it is obvious that it is not restricted thereto but is broad enough to cover all structures that come within the scope of the annexed claims.

115 Having thus described my invention, what I claim is:

1. In a machine of the class described, a button container, a chute leading therefrom, a cover mounted above said chute, and a hinged trap in said cover intermediate its ends, to permit buttons to be placed in the chute independently of the container, said trap having a slotted free end and a spring 120 on its hinge.

125 2. In a machine of the class described, a button chute with a cover thereon, and a trap pivotally mounted in the cover and slotted in its lower end so as to permit a button to be placed true in the chute.

3. In a machine of the class described, a button chute, a button feeding device adapted to engage a button in said chute, means for causing said device to force a button 5 positively in the direction of movement and hold the same, an arm on said button-moving means, a roller on said means, and means for engaging said roller and arm to elevate the button-moving means and hold the same 10 clear of the button on its return movement.

4. In a machine of the class described, a button chute having a gate at its lower end, said gate being provided with slots in its end, a finger adapted to enter said slots and 15 means for shifting said finger so as to force a button under said gate and a pivoted arm on said finger adapted to raise said finger on its return movement.

5. In a machine of the class described, a 20 button chute with a cover, a cam on said cover with a pin projecting therefrom, a finger adapted to shift buttons and a pivoted arm mounted on said finger and adapted to engage said pin and raise said finger on its 25 return movement, but not otherwise.

6. In a machine of the class described, a 30 button chute, a hinged gate adjacent the lower end of said chute, a pivoted arm and means for actuating the same, a finger pivoted on said arm and actuated thereby for moving a button, a spring pressed pivoted arm on said finger and means for engaging said arm to cause the finger to lift and free 35 itself from the button on its rearward movement.

7. In a machine of the class described, a button chute, an arm pivoted to one side of 40 said chute, mechanism engaging the lower end of said arm and actuating the same, a finger pivoted to the upper end of said arm, the free end of which is adapted to engage a button in the chute and move the same forward, a spring pressed pivoted arm on said 45 finger and means for engaging said arm and causing the same to lift the finger on its rearward movement.

8. In a machine of the class described, a button chute, a guard mounted above said chute, a hinged gate secured on the lower 50 end of the guard, a spring for normally holding said gate in position to close the end of the chute, a pivoted arm secured to the side of the chute and mechanism for actuating the same, a finger pivoted to the upper 55 end of said arm and adapted to be recipro-

cated by the movement of said arm, a spring pressed arm pivotally secured to said finger and a stop on the guard adapted to engage said arm and lift the finger clear of the chute on the rearward movement of said finger. 60

9. In a machine of the class described, a button chute, a guard on said chute, a hinged gate secured to the lower end of said chute, said gate having slots in its end, a reciprocating finger having a bifurcated free end 65 adapted to pass through the slots in the gate and move a button from under said gate, a stop and cam on the guard, a pivoted arm on the finger, and a roller on said finger, said arm and roller adapted to engage the 70 stop and cam on the rearward movement of the finger whereby said finger is lifted out of engagement with buttons in the chute.

10. In a machine of the class described, a button chute, a guard secured above said 75 chute, a hinged gate secured to the lower end of said guard, a pivoted arm secured to the side of the chute, mechanism for engaging the lower end of said arm and actuating the same, a finger pivoted to the upper end of 80 said arm, the free end of said finger being bifurcated to engage a button through slots in the hinged gate, a bearing on said finger, with a roller mounted therein, a cam on the guard engaged by said roller on the rear- 85 ward movement of the finger, a pivoted arm on the finger, and a stop on the guard engaging said arm on the rearward movement of the finger and lifting said finger free of the buttons in the chute on said rearward 90 movement.

11. In a machine of the class described, a button container, a button chute leading therefrom, a cover mounted above said chute, a trap mounted in said cover adjacent the 95 container, a slotted, hinged gate mounted on the cover adjacent the lower end of the chute, means mounted between the trap and hinged gate and above the chute for engaging a button in the chute and forcing the 100 same under the gate, an arm on said means, a roller on said means, and means on the cover for engaging said arm and roller and elevating said button moving means on its return movement. 105

Signed at the city of Bridgeport, county of Fairfield, State of Connecticut, this 29th day of August, 1916.

BORIS DUBI.
